UNITED STATES PATENT OFFICE.

WILLIAM B. BASTIAN, OF CHICAGO, ILLINOIS, ASSIGNOR TO BASTIAN-MORLEY CO.,
OF PIERRE, SOUTH DAKOTA, A CORPORATION OF SOUTH DAKOTA.

GAS WATER-HEATER.

1,072,072. Specification of Letters Patent. Patented Sept. 2, 1913.

Application filed September 30, 1912. Serial No. 723,139.

To all whom it may concern:

Be it known that I, WILLIAM B. BASTIAN, a citizen of the United States, residing at Chicago, in the county of Cook and State 5 of Illinois, have invented certain new and useful Improvements in Gas Water-Heaters, of which the following is a specification.

The subject of the present invention is a gas water-heater of the class shown and described in Letters Patent No. 1,013,581, which were granted June 2, 1912, and for which I filed an application on January 28, 1911, Serial No. 605,225, and the object of the invention is, generally stated, to improve the construction of the gas water-heater shown, described and claimed in said Letters Patent, particularly with relation to the general arrangement of the several parts thereof and the general adaptation thereto of the particular burner shown, described and claimed in Letters Patent No. 1,040,986 granted October 8, 1912.

A further object of the invention is to improve the construction of that part or element of a water-heater of that class to which the invention relates, which is known as and commonly called the "spreader", being in fact a part having internal spaces in which the water is contained and through 30 which the water circulates while subjected to the heat generated in the heater, whereby the water is heated and in consequence thereof caused to circulate.

For the sake of clearness it may here be 35 stated that adhering to the commonly recognized nomenclature of the art, the term "boiler" will be used in this specification to designate that part of the apparatus which is, in fact, a tank adapted to contain 40 a comparatively large volume of water and which serves as a storage tank or reservoir for the hot water and through which a constant circulation is maintained when water is not being drawn off from the "service 45 pipe", this latter term being used to designate that pipe through which the water is carried off from the water-heater to the point at which it is to be used, either for domestic purposes, or for heating the radiator or radiators of a heating system.

The term "heater" is used to designate 50 those portions of the apparatus for producing the heat and applying it to the spreader (so-called), and the term "burner" is used 55 to designate that portion of the apparatus

which is adapted to burn any suitable fuel for supplying the necessary heat.

The invention consists in the features of novelty that are hereinafter described with reference to the accompanying drawings 60 which are made a part of this specification and in which—

Figure 1 is a sectional elevation of a gas water-heater embodying all of the several features of the invention in their preferred 65 forms. Fig. 2 is a perspective view of the spreader in its preferred form. Fig. 3, is a plan view of a spreader of modified construction. Figs. 4 and 5 are axial sections thereof on the lines 4—4 and 5—5, Fig. 3, looking into the direction of the arrows, respectively.

1 represents a tank, called the boiler, 2 a cold water supply pipe, 3 a circulating pipe, and 4 the service pipe. Preferably 75 the cold water supply pipe extends through the crown of the boiler and downward thereinto, terminating at any desired distance from the bottom, 5, thereof, and preferably this service pipe extends through the crown 80 of the boiler and terminates near the top thereof. The upper end of the circulating pipe, 3, communicates with the service pipe, 4, near the top of the boiler. As before intimated, the boiler forms in fact a reservoir 85 through which a circulation is maintained when water is not being drawn off from the service pipe and, in addition thereto, a storage tank in which the water is stored as it 90 is heated, so that when water is drawn off from the service pipe it will be taken from the upper part of the boiler, where it is of the highest temperature. The lower end of the circulating pipe, 3, communicates with the top of the spreader, 6, and the bottom 95 of the spreader communicates with one end of a circulating pipe, 7, the other end of which extends through the bottom, 5, of the boiler and communicates with the interior thereof. The spreader, 6, and the circulating pipe, 7, are contained within a combustion chamber, 1^b, which is formed by a downward extension, 1^c, of the boiler and the lower end of this extension rests upon a supporting ring, 8, which is supported by the spreading arms, 9, of a foot or pedestal, 10.

The spreader is made of what may be called two plates, 11 and 11^b, of circular outline, although they are cast integrally and connected at their peripheries by a portion of 100 105 110

the casting comprising them, so that they are spaced and held apart. The two plates are of substantially concavo, convex shape and arranged with their concavo sides uppermost, so as to leave between them a comparatively thin internal chamber or passage, 6^b, in which the water is spread out in a thin film or layer with a view to facilitate its being heated.

10 The plates, 11 and 11^b, are continuous, that is to say they are without any openings or perforations through which water can pass, so that the upper plate, 11, being concave, or dished, on its upper side, forms a drip pan in the manner and for the purpose herein after described. The spreader has also a plurality of passages, 12, above the space or chamber, 6^b, which connect and afford communication between the outer portion of said chamber, 6^b, at different points, and the lower end of the circulating pipe, 3. There may be any desired number of these passages and they are preferably formed in, or rather are afforded by a plurality of hollow arms or branches, 13, of the integral casting which comprises the entire spreader and its several features, which branches join the peripheries of the plates, 11 and 11^b, at distant point, whence they preferably extend upward and inward and come together in a hollow spud, 14, which is preferably internally screw-threaded and engages the correspondingly externally threaded end of the circulating pipe, 3. Any desired number of these hollow branches may be used and they may be inclined upward and inward, and radiate after the manner of the spokes of a wheel, as shown in Figs. 1 and 2, or they may lie in a plane perpendicular to the axis of the spud, 14, or horizontally, as shown in Figs. 3, 4 and 5. But preferably they incline upward and inward because when in this position they facilitate circulation better than they would if horizontal. As shown in Figs. 1 and 2, each branch is apart from the top wall, of the circulating chamber 6^b, although they are integral with the plate, 11, which forms this top wall, while in the form shown in Figs. 3, 4 and 5, the branch in which the passageway, 12, is formed is a mere rib, 13^b, on the top of the plate, 11, of the chamber 6^b. In any event the spreader is below and directly in the vertical line of a flue, 15, for the purpose hereinafter described. With this arrangement, assuming that no water is being drawn off from the service pipe, as the water enters the spreader through the circulating pipe, 7, it will be spread out in the chamber, 6^b, of the spreader in a thin film or body and as it becomes heated it will rise upward in the space or chamber 6^b, and pass into the hollow branches, 13, thence upward through said branches into the lower end of the circulating pipe, 3, thence up-

ward through said pipe into the service pipe, 4, and thence downward through that portion, 4^a, of the service pipe which extends from its point of communication with the circulating pipe, 3, to the boiler, thence downward into and through the boiler thence downward into and through the circulating pipe, 7, and so on, continuing in a complete circuit so that all of the water in the boiler becomes highly heated. When the service pipe is opened to draw off water it will be supplied from the upper part of the boiler, where it is hottest, and it is in order to prevent cold water supplied through the pipe, 2, from directly entering the service pipe, 4, that said pipe is carried downward to a level near the bottom of the boiler.

15 It is found in actual practice that a spreader constructed in the manner above described is highly efficient, the reason for this being that its construction is such that the water is at no point compelled to flow contrary to natural physical laws. The under side of the spreader has a large area which is subjected to the direct action of the flame, and the effect of heating the water is to cause it to flow upward and downward in all directions from the center of the circulating chamber, 6^b. It is manifest that the effect of this chamber is to form a passageway of constantly increasing capacity in the direction of the flow, and consequently, the velocity of the flow will be least at the extreme outer portion of the chamber. It is at this point that the combustion comes 100 the nearest to being complete, and the heat, therefore, will be greater than at any other part of the chamber. Still obeying the natural physical law, the water thus heated will pass upward and inward, through the passages, 12, which are of ample capacity, and enter the lower end of the circulating pipe, 3'. A reversal of some of the features of this construction are shown in my former Patent, No. 1,013,581, granted Jan. 2, 1912, and while the arrangement there shown gives fairly satisfactory results, it is nevertheless found that in actual practice the arrangement shown in the present application is of the greater efficiency.

115 As before stated, the spreader is contained within the combustion chamber and in order to utilize the heat of the products of combustion after escaping from the combustion chamber, a flue, 15, is arranged so that its 120 lower end communicates with its combustion chamber, 1^b, directly over the spreader, whence it extends upward completely through the boiler, and at its upper end is open for the escape of the products of combustion into a suitable flue or pipe by which they are carried off and ultimately discharged, and the circulating pipe, 3, is arranged concentrically within this flue. The combustion chamber also completely in- 125 130

closes the burner, 16, which is preferably constructed as shown in Figs. 2 and 3 of the drawings.

It will be observed that the spreader is arranged directly beneath the flue, 15, and with its concave side uppermost, and this is important in that when so arranged it serves as a drip cup for catching and retaining the water of condensation which trickles down the circulating pipe, 3, and the interior of the flue, 15. Otherwise this water would fall upon the floor and in some instances would fall upon the burner and extinguish the flame.

15 The burner and its accessories, may be constructed precisely as shown in my aforesaid Patent No. 1,040,986, so that a description of it, in detail, is not here necessary.

20 The burner is provided with a centrally located vertical opening for the passage of the vertical branch, 17, of the circulating pipe, 7, which fits the pipe snugly but loosely enough to permit of the vertical adjustment of the burner. The lower end of the pipe, 17, screws into the vertical branch of an elbow, 18, into the horizontal branch of which screws one end of a short pipe, 19, the other end of which screws into the 25 horizontal branch of an elbow, 20, into the vertical branch of which screws the lower end of the main vertical branch of the circulating pipe, 7. The periphery of the burner is notched to engage the vertical pipe, 7, and the pipe, 19, is provided with right and left threads and is of such length that when turned in the proper direction the burner will be clamped between the vertical branches, 7 and 17, of the circulating 30 pipe, whereby it is adjustably held and supported.

What I claim as new and desire to secure by Letters Patent is:

1. A water-heater having, in combination, 45 a boiler, a spreader formed of two substantially horizontal continuous plates, arranged one above the other and spaced apart so as to leave between them a chamber of substantially saucer shape for the passage of water, a plurality of hollow branches located above said chamber and communicating at their outer ends with the outer portion of said chamber, at different distant points, a water circulating pipe, the lower 50 end of which communicates with the inner end of said hollow branches, and the upper end of which communicates with the boiler, and a second circulating pipe communicating with the boiler and with the bottom 55 end of the spreader at the center of the saucer shaped chamber, aforesaid.

2. A water-heater having, in combination, 60 a boiler, a spreader formed of two substantially horizontal continuous plates, arranged one above the other and spaced apart to

leave between them a saucer shaped space, or chamber, for the passage of water, a plurality of hollow branches the outer ends of which communicate with the outer portion of said chamber at different distant points, whence they extend inward, a circulating pipe the lower end of which communicates with the inner ends of said hollow branches and the upper end of which communicates with the boiler, and a second circulating pipe communicating with the boiler and with the chamber aforesaid of the spreader, the top side of the upper plate aforesaid of the spreader being concave.

3. A water-heater, having, in combination, 65 a boiler, a spreader formed of two substantially horizontal continuous plates, arranged one above the other, the upper side of the lower plate being concave and the under side of the upper plate being convex, said plates being cast integrally, and the casting comprising them having a portion which joins their outer margins or peripheries and spaces and holds them apart so as to leave between them a saucer shaped 70 space, or chamber, for the passage of water, a plurality of hollow branches, the outer ends of which communicate with the outer portion of said saucer shaped chamber at different distant points, whence they extend inward and upward, a circulating pipe, the lower end of which communicates with the inner ends of said hollow branches, and the upper end of which communicates with the boiler, and a second circulating 75 pipe communicating with the boiler and with the saucer shaped chamber, aforesaid, at about its center.

4. A water-heater having in combination 80 a boiler, a combustion chamber located beneath the bottom of the boiler, and formed by a downward continuation of the cylindrical walls of the boiler, a ring upon which the bottom of said downward continuation rests, means for supporting said ring, a 85 spreader located in the combustion chamber, said spreader being formed of two substantially horizontal continuous plates arranged one above the other, the upper side of the lower plate being concave and the under side of the upper plate being convex, said plates being cast integrally, and the casting comprising them having a portion which joins their outer margins or peripheries, and spaces and holds them apart, so as to leave between them a saucer shaped 90 space, or chamber for the passage of water, said casting comprising also a plurality of hollow branches, the outer ends of which communicate with the upper portion of said saucer shaped chamber at different distant points, whence they extend inward and upward, a circulating pipe the lower end of which communicates with the inner ends of said hollow branches and the upper end of 95 100 105 110 115 120 125 130

which communicates with the boiler and a second circulating pipe located within the combustion chamber and communicating at one end with the lower portion of the boiler, 5 through an opening in the bottom thereof, and at the other end centrally with the saucer shaped chamber aforesaid at its lowermost point.

5. A water-heater having, in combination, 10 a boiler, a combustion chamber located below the boiler, a flue communicating at its lower end with the combustion chamber, whence it extends upward through the boiler, a spreader located in the combustion chamber below and immediately opposite the lower end of the flue, a circulating pipe communicating with its lower end with the spreader, whence it extends upward through the flue, its upper end being 15 in communication with the boiler, said spreader being made of two concavo-convex or saucer-shaped plates arranged with their concave sides uppermost, said spreader having also hollow branches communicating 20 with the outer portion of the chamber aforesaid, whence they extend inward and communicate with the lower end of the circulating pipe first aforesaid.

6. A water-heater having, in combination, 20 a boiler, a combustion chamber located beneath the boiler, a spreader located in the combustion chamber, a circulating pipe having two vertical branches and a horizontal branch, said horizontal branch having right 35 and left screw-threads, elbows carried by the

vertical branches and having screw threads complementary to the screw threads of the horizontal branch whereby, when the said horizontal branch is turned, the vertical branches are relatively moved laterally and 40 a burner also located in the combustion chamber and having a vertical opening through which one of the vertical branches of the circulating pipe passes, the other of said vertical branches being adapted to engage the 45 periphery of the burner whereby it is clamped and adjustably held in place.

7. A water-heater having, in combination, 50 a boiler, a combustion chamber located beneath the boiler and formed by a downward continuation of the walls thereof, a ring upon which the bottom of said downward continuation rests, a pedestal having arms supporting said ring, a spreader located in the combustion chamber, a circulating pipe, a portion of which is also located in the combustion chamber and has two vertical branches, one of which communicates with the boiler and the other of which communicates with the bottom portion of the 55 spreader, a burner having a vertical opening through which the latter branch of the circulating pipe passes freely, and means engaging the burner and adjustably supporting it.

WILLIAM B. BASTIAN.
